(57) CLAIM

The ornamental design for a public access interactive kiosk, as shown and described.

DESCRIPTION

FIG. 1 is a left side elevation view of my new and ornamental design for a public access interactive kiosk, with it being understood that the right side elevation view would be a mirror view of this figure;

FIG. 2 is a front elevation view; and,

FIG. 3 is a rear elevation view.

1 Claim, 2 Drawing Sheets

FIG. 1

FIG. 2

FIG. 3
